UNITED STATES PATENT OFFICE.

THOMAS W. McCREARY, OF MONACA, PENNSYLVANIA, ASSIGNOR TO THE PHOENIX
GLASS COMPANY, OF MONACA, PENNSYLVANIA, A CORPORATION OF WEST VIR-GINIA.

DESIGN FOR A FISH BOWL OR SIMILAR ARTICLE.

Application filed May 10, 1928. Serial No. 26,622. Term of patent 7 years.

To all whom it may concern:

Be it known that I, THOMAS W. McCREARY, a citizen of the United States, residing at Monaca, in the county of Beaver, State of Pennsylvania, have invented a new, original, and ornamental Design for Fish Bowl or similar Article, of which the following is a specification, reference being had to the accompanying drawing, forming a part thereof. The figure is a perspective view of a bowl showing my new design.

I claim:

The ornamental design for a fish bowl or similar article, as shown.

THOMAS W. McCREARY.
